UNITED STATES PATENT OFFICE.

GEORGE B. McCORMACK, OF JERSEY CITY, NEW JERSEY.

PRINTING-PRESS.

1,275,281.

Specification of Letters Patent. Patented Aug. 13, 1918.

Application filed October 31, 1916. Serial No. 128,697.

To all whom it may concern:

Be it known that I, GEORGE B. McCORMACK, a citizen of the United States, residing at Jersey City, in the county of Hudson and State of New Jersey, have invented new and useful Improvements in Printing-Presses, of which the following is a specification.

This invention relates to a printing press.

The object of the present invention is to provide a simple, cheaply manufactured, high speed press, and particularly to provide a novel type bed and platen movement.

Further objects will hereinafter appear.

The invention consists of the parts and the construction and combination of parts as hereinafter more fully described and claimed, having reference to the accompanying drawings in which:

Figure 1 is a side elevation of the press partly broken away and in section.

Fig. 2 is a detailed view of the cylinder platen, partly in section showing the position of the paper grippers.

Fig. 3 is an end view of the press.

Fig. 4 is a side elevation partly in section showing the arrangement of the inking rollers.

Fig. 5 is a plan view of the press.

Fig. 6 is a cross section on line VI—VI

Fig. 5, showing the inking rollers and cylinder platen removed.

Fig. 7 is a detailed view partly in section showing the paper gripper operating mechanism.

Fig. 8 is a longitudinal section of the type bed showing the position of the rollers and the guide channel formed in the bed plate of the press.

Fig. 9 is a partial plan view of the gear 8 showing the position of the lateral guiding slots 19.

Referring to the drawings in detail, A indicates the main frame of the press upon which is supported a bed plate 2. Formed in the upper surface of the bed plate is a continuous endless channel consisting of two straight parallel side sections 3 and 4 and a pair of curved connecting end sections 5 and 6.

Journalized on top of the bed plate as at 7 is a bevel gear 8 which is supported upon ball bearings 9 carried by a circular groove 10 formed in the top surface of the bed

plate 2, and intermeshing with said gear is a driving gear 11 which is secured upon a driving shaft 12 carried by bearing brackets 13 secured on or formed integral with the main frame A. The driving shaft 12 is mounted above the gear 8 centrally with relation to same and extends cross wise of the frame A and the bed plate 2. Secured on one end of the shaft just above the straight side of the channel indicated at 3, is a cylinder platen 14 and secured above the other straight side 4 of the channel is an inking roller 15 which is supplied with ink from a fountain 16 and a pair of ductor rollers 17.

The upper surface of the gear 8 is planed off to form a smooth surface which is adapted to support a type bed generally indicated at 18. Formed in the web or surface of the gear 8 is a pair of laterally disposed slots 19 and mounted in each slot is a sliding block 20 through each of which extends a pin 21. The upper end of each pin is secured in the bottom of the type bed 18 while the lower ends are provided with rollers 22 which extend down into the guide channel formed in the upper surface of the bed plate 2. Rotation transmitted to gear 8 through the driving shaft 12 and gear 11 therefore causes the type bed to travel round and round with the gear 8, and predetermined positions of the type bed with relation to the cylinder platen and the inking rollers is obtained by means of the slots 19 and the continuous guiding channel consisting of the straight parallel sides 3 and 4 and the curved connecting end sections 5 and 6, that is referring to the plan view shown in Fig. 5, it can be seen that the pins 21 carrying the rollers 22 will cause the type bed to travel in a straight line in the direction of arrow a while it is passing under the cylinder platen 14. A continued movement of the gear and type bed will cause the rollers to strike the curved connecting end section 5 and consequently turn the type bed around as shown by dotted lines at 18^a, see Fig. 5. A continued movement will again cause the type bed to straighten out as it enters the channel 4 or while it passes into engagement with the inking rollers. The type bed is again given a turning movement as it passes around the curved connecting end section 6, and is finally straightened out as it

55 60 65 70 75 80 85 90 95 100 105

enters the straight side of the channel indicated at 3.

From the foregoing it will be seen that the type bed will continuously travel in unison with the gear 8 in a continuous circuit, and that its movements are guided and controlled entirely by the continuous guiding channel described. Reciprocating or intermittent movements are in this manner entirely obviated and comparatively high speed may therefore be obtained without racking or subjecting the press as a whole to unnecessary strains.

The simple driving connection between the type bed and the main drive shaft 12, is thus permitted, as the only connection required is the gear 8 having the laterally disposed slots 19 formed therein together with the pins 21 and rollers 22. The cylindrical platen employed is directly secured upon the main driving shaft 12 and as the gears 11 and 8 are driven at the ratio of 2 to 1, it can readily be seen that the cylinder platen will make two complete revolutions while the bed plate completes one cycle of its continuous traveling circuit.

The grippers generally indicated at 25, see Fig. 2, with which the platen is provided, should therefore be opened and closed only once during each two revolutions. This is accomplished in the following manner: Formed in the face of the gear 8 is a continuous annular groove 26 into which extends the lower end of a rocker arm 27. This rocker arm is pivotally mounted as at 28 on an extension 29 formed on the bearing bracket and its upper end is connected with the upper end of a crank arm 30. The crank arm is pivotally mounted on the same bearing extension, while its lower end is pivotally connected as at 31 with a pair of lugs formed on a plate 32. The upper end of the rocker arm 27 is fork shaped, in this manner providing two pivots 28 and similarly necessitating the provision of two crank arms 30 and the connecting lugs 31. The plate 32 is slidably mounted on the shaft 12 and is therefore adapted to be moved to and away from the end of the cylinder platen when the rocker arm 27 is swung about its pivots 28 by means of the undulations 33 formed in the annular groove 26.

The grippers 25 are secured upon a shaft 34. Secured on the same shaft is a semi-circular plate 35 in which is formed a cam groove 36. Slidably mounted in the platen adjacent said semi-circular platen, is a bar 37 which is directly secured to the plate 32 as indicated at 38. Projecting inwardly from the bar 37 is a pin 39 which engages the cam groove 36 formed in the semi-circular plate 35. Sliding movement of the plate 32 with connected bar 37 in this manner causes the pin 39 which projects through

the slot 36 to partly turn the semi-circular plate 35 and the attached shaft 34 which carries the grippers 25, in this manner opening or closing same as the case may be.

Any suitable feeding mechanism may be employed for the purpose of delivering the sheets to be printed to the cylinder platen when the grippers are in open position. In the present instance a table 40 has been provided to which the sheets may be delivered by an automatic feeder or by hand. The sheet delivered at this point is engaged by the grippers 25 and thus wrapped about the cylinder or platen at the time when the type bed passes into engagement. The impression is in this manner made and the sheet may consequently be released immediately thereafter or at the point indicated at 41 where a plurality of stripping fingers 42 are shown. The grippers are here automatically released as the offset 33 formed in the annular groove 36 is so arranged and positioned as to rock the arm 27 to release the grippers, the paper received by the stripping fingers being then removed by the conveyer 43 or any other suitable mechanism.

The inking roller indicated at 15 may engage directly with the type bed if desired, or a second form roller 15^a may be provided for the purpose of more equally distributing the ink. While a specific arrangement of inking rollers are here provided, it is obvious that any other form or arrangement may be employed, the real novelty presented by the present structure being the type bed movement and the automatic opening and closing of the grippers.

The materials and finish of the several parts of the device may otherwise be such as the experience and judgment of the manufacturer may dictate.

I wish it understood that various changes in form, proportions and minor details of construction may be resorted to within the scope of the appended claims, and that I do not wish to limit myself to the specific design or construction here shown.

Having thus described my invention, what I claim and desire to secure by Letters Patent is:

1. In a printing press, a rotatable member, a shaft extending diametrically across the member, a cylinder roller and an inking roller each mounted on said shaft and over the rotatable member, a type carrying bed mounted on said rotatable member, and means whereby said bed will partake of the rotary movement of said member and will be moved relative to the member so as to move in straight paths beneath each of the rollers.

2. In a printing press, a rotatable gear, causes the pin 39 which projects through a type carrier thereon, a shaft extending

diametrically across the gear, a pinion on the shaft meshing with the gear to drive the latter, a cylinder roller and an inking roller each mounted on said shaft so as to be driven by said pinion, and means whereby said carrier will be moved so as to travel in straight paths beneath each of said rollers.

In testimony whereof I have hereunto set my hand in the presence of two subscribing witnesses.

GEORGE B. McCORMACK.
